STERILIZER CABINET

Joseph Palma, Jr., Wheaton, Ill., assignor of 12/30 to Alfred Vischer, Jr., 2/30 to William Vischer, 2/30 to Alfred Vischer III, 2/30 to Alfred Vischer, Jr., as trustee, 4/30 to Walter W. Zitzewitz, 4/30 to Elmer K. Zitzewitz, 1/30 to Gertrude J. Zitzewitz, 1/30 to Barbara O. Zitzewitz, and 2/30 to Gertrude V. Bouton

Application March 11, 1957, Serial No. 45,176

Term of patent 14 years

(Cl. D83—1)

Fig. 1

Fig. 2

Fig. 3

Fig. 4

Fig. 1 is a perspective view of a sterilizer cabinet embodying my new design;

Fig. 2 is a top plan view of the cabinet;

Fig. 3 is a side elevational view of the cabinet; and

Fig. 4 is a front view thereof.

The essential features of my design reside in the portions shown in full lines.

I claim:

The ornamental design for a sterilizer cabinet, substantially as shown and described.
